Inventor:

Geo. W. Wilson

United States Patent Office.

GEORGE W. WILSON, OF FREEPORT, ILLINOIS.

Letters Patent No. 96,857, dated November 16, 1869.

IMPROVED WASH-BOILER.

The Schedule referred to in these Letters Patent and making part of the same.

To all whom it may concern:

Be it known that I, GEORGE W. WILSON, of Freeport, in the county of Stephenson, and State of Illinois, have invented certain Improvements in Wash-Boilers, of which the following is a specification.

The nature of my invention consists in constructing a cover for a wash-boiler with sides projecting downward to or nearly to the bottom of the boiler; in attaching partitions thereto; and in providing it with a valve, so that when the cover is held in place in the boiler, steam-pressure may be obtained to a certain degree, and a circulation of water be produced without the use of a diaphragm or false bottom.

Description of the Accompanying Drawings.

Figure 1 is an isometrical perspective.

Figure 2, a vertical section on red line x y.

General Description.

A represents a boiler made in any convenient form, and of the usual material.

B, the cover, which is made to fit the boiler closely, as shown.

At the ends of this cover, or at the sides, as may be convenient or best accommodate the interior space, I attach the plates or partitions C.

The sides of the cover are made to descend to the bottom of the boiler, or into the water therein, and so attached to the top that the cover will be steam or air-tight.

The partitions or plates C are so attached that their lower edges will be about the same distance from the bottom of the cover as they are placed from the sides or ends of the cover. Their upper edges are brought nearly up to the top of the cover, so as to leave a small space at the top for the outflow of water, or they may be brought up, and attached to it. In this case a row of holes is made near the top of the cover, sufficiently large or numerous for the outflow.

I provide this cover with locks or catches D, so as to prevent the steam from forcing it out of the boiler, or raising it so that its lower edge will come above the water.

When the cover descends below the top of the boiler, these catches or locks are applied, as shown.

The cover may, however, project considerably above the boiler, if desired. In that event, hooks or other catches will be required, and also a flange around the boiler, to hold or return any water which may be forced out between the cover and the boiler.

As with a cover of this construction fastened to the boiler, an explosion might occur, I provide the top with a safety-valve, E, which is balanced to retain as much steam as is safe with tin or other sheet-metals, and should not, for these metals, permit a pressure of more than one pound to the square inch, and it is advisable to have it still less than that amount. The air escapes through this valve when the cover is pressed down, and in order to prevent it from becoming clogged, or its action impaired by the clothes in the boiler, or by lint, I usually place a board over it for protection.

Operation.

In operation, the usual quantity of water is placed in the boiler, and when ready the clothes are placed in it, and the cover pressed down and fastened.

When the water boils, the texture and weight of the clothes will prevent the steam from passing readily through the body of the boiler, and will create a pressure sufficient to force the water through the space or spaces between the sides of the cover and the plates C, as indicated by the arrows, and cause a thorough circulation of the water, without the intervention of a diaphragm or horizontal plate at the bottom.

This device will also operate if the partition-plates C are not brought as near the bottom as shown, but I prefer to bring them near the bottom.

Having thus fully described my improvements in wash-boilers,

What I claim as new, and desire to secure by Letters Patent, is—

The cover B, when provided with one or more partitions C and valve E, in combination with boiler A, constructed as herein described, for the purpose specified.

GEO. W. WILSON.
